NEEDLE THREADER

Paul E. Irwin, Brooklyn, N. Y., assignor to Cotter Products Inc., New York, N. Y., a corporation of New York

Application July 27, 1949, Serial No. 4,162

Term of patent 7 years

(Cl. D3—19)

To all whom it may concern:

Be it known that I, Paul E. Irwin, a citizen of United States, residing at Brooklyn, in the county of Kings and State of New York, have invented a new, original, and ornamental Design for a Needle Threader, of which the following is a specification, reference being had to the accompanying drawing, forming part thereof.

In the drawing:

Fig. 1 is a front elevational view of a needle threader showing my new design;

Fig. 2 is a rear elevational view thereof;

Fig. 3 is an end elevational view thereof, both ends being identical; and

Fig. 4 is a top plan view thereof.

I claim:

The ornamental design for a needle threader, as shown and described.

PAUL E. IRWIN.
